EXCAVATOR

Frederik Hendrik Bakker, The Hague,
Netherlands

Application December 19, 1933, Serial No. 703,067

6 Claims. (Cl. 37—115)

This invention relates to a scraper or excavator bucket of the bottomless type which is drawn to and fro over the ground by means of several cables and the scraper bucket has means to regulate the depths of excavation in every point of the path during the working of the same. This device regulates the depth of excavation in a fashion similar to that set forth in my Dutch Patent No. 31,138.

When the excavator bucket is drawn forward during the working period the depth or extent of excavation can be regulated by the use of a rocking knife. This rocking knife can be placed in various positions by the operation of several cables used with excavator buckets of this type. These cables are operated at different times in order to fix the knife in its desired position. The cables are referred to as steering cables, pulling cables and back pulling cables. When the bucket is full or when it is desired to discontinue the excavation with the bucket, the steering cable is braked. The braking of this cable results in a force being applied on the bucket contrary to the pulling force in the pulling cable and the resulting force on the bucket is equivalent to the pulling force in the pulling cable, minus the braking force in the steering cable. Since the braking force represents a loss of power, it is necessary, in order to have the device function as efficiently as possible, to reduce the loss of power to a minimum.

It is therefore an object of this invention to reduce the loss of power to a minimum.

This is accomplished by the use of a rocking knife which can be placed in different positions during the working of the machine. This is done by the braking of the steering cable or the back pulling cable which causes the knife to move into its proper position notwithstanding the pressure of the earth on the knife which tends to force the same into another position.

It is further to be noted that the rocking knife may be locked in a number of intermediate positions as well as extreme positions which are not changed by the pressure of the earth on said knife.

The invention is set forth in the drawing which discloses two types of excavator buckets. Figure 1 discloses a side view of a scraper bucket in which the digging knife may be placed in two extreme positions. Fig. 2 discloses a cross section of a steering coupling which may be used in place of the wheel shown in Figure 1 which allows the knife to be locked in several intermediate posi-

tions. Fig. 3 shows a longitudinal section of the steering coupling shown in Fig. 2.

The scraper bucket 1 is drawn over the ground during the working period of the device by means of a pulling cable 2. A U-shaped knife 4 having a cutting edge 3 is pivoted to said scraper bucket 1 at 14, so that it can be placed in several digging positions. A connecting rod 7 is coupled by means of an axle 8 to the top end 5 of the knife 4. The opposite end of this connecting rod 7 is connected to a pin 8 which is rigidly connected to a rotatable cable wheel 9. This cable wheel is movable around an axle 10, which axle is rigidly connected to the side plates 11 of the scraper bucket 1. The steering cable 12 and the back pulling cable 13 are connected to the circumference of the wheel 9 at various points to move the wheel in opposite directions. The ends of the pin 8 move in circular slots in the side plates 11. These slots contain the ends 15 and 16 which limit the extent of the movement of the pin 8 and therefore fix the extreme positions for the digging knife.

The operation of this device is as follows: During the working period the back pulling cable 13 is braked which causes the cable wheel 9 to turn in a counterclockwise direction. The movement of the cable wheel 9 in a counterclockwise direction causes the connecting rod 7 to move to the left and the knife 4 which is rigidly pivoted to said connecting rod falls forward and thereby allows the cutting edge 3 to dig into the soil of the earth. This position of the cutting edge of the knife is indicated in Fig. 1 of the drawing by dotted lines.

It may be desirable during the working period to have the cutting edge of the knife withdrawn from the ground. This is accomplished by braking the steering cable 12. The braking of the steering cable causes the cable wheel 9 and the pin 8 to move in a clockwise direction. This movement of the wheel and pin causes the connecting rod 7 to move to the right. This operation therefore causes the knife 4 to fall backwards into a position as indicated in Fig. 1 of the drawing by full lines.

The radius of the circle made by the movement of the pin 8 mounted on the cable wheel 9 must be chosen in such a way that the pin passes for a short distance during the last portion of the rocking motion an imaginary connecting line of the points 6 to 10. In its extreme positions the pin passes the dead points of this imaginary line and as a result it cannot be dislocated by pressure or tension in the connecting

rod 7. This particular feature also allows the release of the braking force which might be made to the steering cable or the back pulling cable.

5 In case it is desirable to position the knife in intermediate positions, the cable wheel is replaced by a steering coupling such as the device shown in Figs. 2 and 3. It is particularly desirable to place the knife in intermediate positions
10 where the excavation is made on a broken slope or is passed over thin layers of earth. In this steering coupling the axle 10 is replaced by a ratchet wheel 17 which has teeth. The teeth of this ratchet wheel are positioned so that they
15 point in a clockwise direction. The ratchet wheel is suitably connected to the plates 11 of the scraper bucket by means of a fixed axle with key and keyway or, as shown in the drawing, by several bolts 18. Around the ratchet wheel 17 are formed circular running surfaces which
20 are surrounded by two circular plates 19 rigidly connected to each other by means of the locks 20, bolts 21 and 22 and the pin 8. The pawls 23 of the ratchet wheel construction have tail
25 pieces 24 which can pivot about the bolts 22 and pin 8. These pawls are ordinarily urged against the ratchet wheel 17 by means of the springs 25 which may be connected to the bolts 21 in the blocks 20. While the number of these pawls
30 may be varied, the drawing discloses the use of only three.

Around the plates 19 previously referred to there is rotated the pulley ring 26 which has in its outer circumference cable grooves upon which are secured the ends of the steering cable 12 and the back pulling cable 13. The ends of these two cables are wound around said ring in opposite directions so that the ring may be turned in a clockwise or counterclockwise direction, according to the desires of the operator. The amount of rotation of this ring 26 in relation to the plates 19 is limited by the cams 27 on the blocks 28 which cams alternatively push against the points 29 and 30 of the ring 26.

45 The cams 38 are mounted on the inner surface of the ring 26 in order to push against the tail pieces 24 of the pawls 23 when the ring 26 is turned in a counterclockwise direction. If the ring is turned further to the left, the cam 38
50 pushes the tail pieces 24 inwardly against the pressure of the springs 25 and moves the pawls 23 free from the ratchet wheel 17.

The operation of this type of scraper is as follows: When the bucket is pulled forward and no braking force is exerted on the steering cable or on the back pulling cable the soil of the ground pushes against the cutting edge 3 of the blade 4 and causes this knife to fall forward (see dotted lines of Fig. 1). As a result of this, the connecting rod 7 and the pin 8 are pulled forward. During this movement to the left, or in a counter-clockwise direction, the tail pieces 24 of the pawls 23 become free from the cams 30. After this movement the springs 25 press these tail pieces outwardly and cause the pawls to be pressed between the teeth of the ratchet wheel 17. This results in the placing of the knife in a fixed intermediate position which may not be changed by the pressure of the soil.

70 If it is desired to dig a deeper cut in the ground the back pulling cable is braked. This causes the ring 26 to turn to the left and the cams 30 to press the tail pieces 24 inwardly. This results also in the pawl becoming free from 75 the ratchet wheel 17. Due to the tension of the

connecting rod 7 caused by the pressure of the ground on the cutting edge 3 of the knife 4, the pin 8 is also moved to the left and this causes the tail pieces 24 to become free from the cams 30 so that the pawls 23 catch behind the teeth of the ratchet wheel 17. By continuous or repeated manipulation of the device as herein mentioned, the digging knife can be made to fall forward in its extreme position. 5

It also might be desired during the operation 10 of the device that there be no digging into the earth. This is accomplished by braking the steering cable which causes the ring 26 to turn to the right until the points 28 on said ring press against the cams 27 of the blocks 20. Upon further movement of the rings 26 the blocks 20 and the pin 8 are moved to the right and the pawls slide over the teeth of the ratchet wheel 17. As soon as the braking force in the steering cable stops, the pulling force of the connecting rod 20 7 pulls the pin 8 to the left until the pawls engage the teeth of the ratchet wheel and lock the knife in a fixed position such as shown in the full lines for the knife in Fig. 1 of the drawing.

When it is desired to pull the bucket back-
wards, the back pulling cable 13 first turns the
ring 26 to the left which results in the pawls
23 being lifted from the ratchet wheel 17. The
points 29 of the ring 26 then come into contact
with the cams 27 and pin 8 which are likewise
caused to rotate to the left. The rotation of the
pin 8 to the left is accomplished against the
pressure of the connecting rod 7 created by the
pressure of the ground against the back side
of the knife 4. As a result of this constant pull-
ing force in the back pulling cable 13, the ring 26
and the pin 8 are turned into the extreme position
whereby the knife is pressed into its forward ex-
treme position so that the back side of the knife
cannot dig itself into the ground. 40

The detailed description above describes the invention proposed but applicant desires it to be known that his device may be completed and operated by other types of mechanism.

What I claim is:—

What I claim is:

1. In a digging scraper bucket of the bottomless type, cable means for moving said scraper over the ground, a digging knife pivotally mounted upon said bucket and means for rocking said digging knife to several angular positions with respect to the horizontal and means connected with said rocking means for locking said digging knife in its desired digging position, all of said means being operable during the movement of the scraper bucket over the ground.

2. In a digging scraper bucket of the bottomless type, cable means for moving said bucket over the ground, a rocking knife pivotally mounted on said bucket, means for moving said rocking knife to several angular positions with respect to the horizontal, and means connected with said rocking means for locking said knife in its desired digging position, all of said means being operable during the movement of the scraper bucket over the ground. 60 65

3. In a digging scraper bucket of the bottom-less type, cable means for coming said bucket over the ground, a U-shaped digging knife pivotally mounted on said bucket, means for rocking said U-shaped digging knife to several angular positions with respect to the horizontal, and means connected with said rocking means for locking said knife in its desired digging position, all of said means being operable during the 75 70

movement of the scraper bucket over the ground. 4. In a digging scraper bucket of the bottomless type, cable means for moving said bucket over the ground, a digging knife pivotally mounted upon said bucket, an oscillating cable wheel movable by a pair of cables for moving said knife into several angular positions with respect to the horizontal, and means connected with said cable wheel for locking said knife in the desired digging position, all of said means being operable during the movement of the bucket over the ground.

5. In a digging scraper bucket of the bottomless type, cable means for moving said bucket over the ground, a digging knife pivotally mounted upon said bucket, means for rocking said knife into several angular positions with respect to the horizontal, and a pawl and ratchet mech-

anism connected with said rocking means for locking said knife in the desired angular position, all of said means being operable during the movement of the bucket over the ground. 5

6. In a digging scraper bucket of the bottomless type, cable means for moving said bucket over the ground, a digging knife pivotally mounted upon said bucket, an oscillating cable wheel movable by a pair of cables for moving the knife about its pivot into a desired angular position with respect to the horizontal, and a pawl and ratchet means for locking said knife in said desired position, all of said means being operable whereby said knife may be moved into several different angular positions and locked therein 10 during the movement of the bucket over the ground. 15
